INTERNAL COMBUSTION ENGINE

Howard A. Guilford and Emerson L. Soland,
Minneapolis, Minn.

Application April 2, 1932, Serial No. 602,716

6 Claims. (Cl. 123—56)

Our invention relates to multiple cylinder internal combustion engines and has for an object to provide an engine in which the moving parts are completely balanced.

5 Another object of the invention resides in providing an engine in which explosion in one cylinder is cushioned through compression in another cylinder by means rigidly connecting together the pistons of said cylinders.

10 Another object of the invention resides in providing a crank shaft having a yoke connected thereto and in employing a plurality of cylinders each having pistons therein, all of the pistons being rigidly connected to said yoke.

15 A still further object of the invention resides in disposing some of the cylinders on one side of the yoke and a corresponding number of cylinders on the opposite side of said yoke.

A feature of the invention resides in arranging 20 certain of said cylinders in alignment.

An object of the invention resides in arranging the cylinders symmetrically with respect to a plane containing the axis of the crank shaft and parallel to the direction of travel of the yoke.

25 Another object of the invention resides in providing an engine in which a lesser number of moving parts are present than in an ordinary internal combustion engine.

A feature of the invention resides in providing 30 an engine in which two piston structures are employed on the same side of the crank shaft, said piston structures being arranged so that the resultant of the pressure on the one occupies identically the same position as the resultant of 35 the pressure on the other.

Another object of the invention resides in constructing said pistons of such area that the magnitude of the resultants on each piston structure is the same.

40 A feature of the invention resides in providing an engine in which lateral stresses on the pistons such as are occasioned through swinging connecting rods are entirely eliminated and in which stresses on the crank shaft are reduced.

45 Another object of the invention resides in providing an engine in which the piston exerts effort upon the crank shaft throughout a greater angle of rotation of the crank shaft than in the usual type of internal combustion engines using 50 swinging connecting rods.

An object of the invention resides in providing an engine which will be exceedingly light in weight.

55 A feature of the invention resides in providing

an engine in which the size and number of bearings required for the engine is reduced.

Other objects of the invention reside in the novel combination and arrangement of parts and in the details of construction hereinafter illustrated and/or described. 5

In the drawings:

Fig. 1 is a plan sectional view of our invention taken through different cylinders thereof.

Fig. 2 is an elevational sectional view taken 10 on line 2—2 of Fig. 1.

Fig. 3 is an elevational sectional view taken on line 3—3 of Fig. 1.

Fig. 4 is an elevational sectional view taken 15 on line 4—4 of Fig. 1.

Fig. 5 is a diagrammatic view showing the cycles of operation of the engine.

Our improved engine comprises a crank case indicated in its entirety at 10, which crank case is rectangular in form, being constructed with 20 side walls 11 and 12, end walls 13 and 14, and a bottom 15, said crank case being open at the top. Within the crank case 10 are formed two partitions 16 and 17 which divide the crank case in three compartments 18, 19 and 20. The partitions 16 and 17 and the end walls 13 and 14 are provided with bearings 21, 22, 23 and 24 in which a crank shaft 25 is journaled. The walls 13 and 14 and the partitions 16 and 17 are each constructed with V-shaped openings 26 best shown 30 in Fig. 2 which extend down to said bearings. The bearings 21, 22, 23 and 24 are formed in halves, the lower half being designated at 27, which halves are attached to the crank case proper. The upper halves of these bearings consist of caps 28 which are bolted to the halves 27 in the customary manner. When the caps 28 are removed the entire crank shaft 25 may be dropped down upon the lower halves 27 of said bearing, through the V-shaped openings 26 in 40 the various end walls and partitions of the crank case. 35

For the purpose of closing the opening through the upper portion of the crank case 10 a closure 32 is employed which is bolted, through cap screws 33, to flanges 34 and 35 formed on the upper edges of the side walls 11 and 12. This closure is constructed with depending flanges 36 and 37 at the ends thereof, which lie in continuation of the end walls 13 and 14 of the crank case as clearly shown in Fig. 3. The openings 26 in the end walls 13 and 14 of crank case 10 are closed by means of cover plates 29 and 30 which are bolted to said end walls and to the flanges 50 55

36 and 37 of closure 32 through cap screws 31.

The crank shaft 25 is best shown in Fig. 1. This crank shaft consists of a number of disks 38, 39, 40, 41, 42 and 43 which are arranged in 5 pairs disposed within the various compartments 18, 19 and 20. Between the two disks 38 and 39 is provided a crank pin 44 which connects the said disks together. In like manner between the disks 40 and 41 is provided a crank pin 45 and 10 similarly between disks 42 and 43 is provided a crank pin 46. The various pairs of disks are connected together through shaft sections 47, 48, 49 and 50 which are journaled in the bearings 21, 22, 23 and 24 previously referred to. The 15 crank pins 44, 45 and 46 are arranged 120 degrees apart so that the impulses from the combustion of the fuel may be uniformly distributed. The disks 38, 39, 40, 41, 42 and 43 serve as fly wheels thereby eliminating the necessity of a 20 single fly wheel upon the exterior of the crank case.

From an inspection of the drawings it will be seen that the cylinders of the invention are arranged in three units designated at 51, 52 and 25 53, each of which units having piston structures connected with the respective crank pins 44, 45 and 46. Since each of the three units 51, 52 and 53 are identical in construction, excepting that they operate upon crank pins angularly disposed 30 with respect to one another, only the unit 51 will be described in detail, which is best shown in Fig. 2. To the side walls 11 and 12 of crank case 10 are attached two cylinder blocks 54 and 55, which extend outwardly from the crank case in 35 opposite directions. The cylinder block 54 comprises cylinders 56, 57 and 58 while the cylinder block 55 comprises cylinders 59, 60 and 61. Both the cylinder blocks 54 and 55 are identical in construction. The cylinder block 54 comprises a 40 base portion 62 which extends throughout the height of the engine and which is rigidly bolted to the end wall 11 through bolts 63. The bores 64, 65 and 66 of the three cylinders 56, 57 and 58 extend through the base portion 62 of the cylinder block 54 and communicate with the chamber 18 through an elongated opening 67 in the side wall 11. Slot 67 extends throughout the entire height of the machine and serves a purpose to be later described in detail. The base portion 62 45 covers the elongated opening 67 throughout its extent so that the entire interior of the crank case is completely enclosed.

Secured to the end of the cylinder block 54 is a cylinder head 69 which is provided with pockets 70 lying at the ends of the bores 64, 65 and 66 of the cylinders 56, 57 and 58. The cylinder head 69 is constructed with pairs of valve chambers 71 and 72 which are connected to suitable manifolds 73 best shown in Fig. 2 whereby a combustible gas may be led into the various cylinders and the spent gases exhausted therefrom. The valve chambers 71 and 72 are closed through 50 poppet valves 74 and 75 which are constructed with valve heads 76 and valve stems 77 slideable 55 in suitable guides 78 in the cylinder head. The heads 76 are seated against valve seats 79 and the said heads are held in engagement therewith through suitable compression coil springs 80. When the valve stem 77 is depressed the valves 60 are open and communication is had through the various manifolds and valve chambers with the bores of the respective cylinders in the ordinary manner.

The cylinders 56, 57 and 58 and the cylinder head 69 are surrounded by water jackets 68

whereby a suitable cooling liquid may be circulated about said cylinders to maintain the same at the proper temperature.

Within the various cylinders 56, 57, 58, 59, 60 and 61 are disposed pistons 81, 82, 83, 84, 85 and 5 86 which reciprocate within the bores of said cylinders in the ordinary manner. These pistons are all rigidly connected to a cross head 87 which is in the nature of a yoke and through which translatory movement of said pistons is transformed to rotary motion and imparted to the crank shaft 25. The cross head 87 consists of two plates 88 and 89 which are spaced from one another to provide a slot 90 therebetween. A block 91 journaled on the crank pin 44 is 10 slideable transversely of the crank case in the slot 90 of the cross head or yoke 87. The two plates 88 and 89 are held spaced from one another through two spacer sleeves 94 and 95 which are disposed between said plates at the extreme upper and 15 lower ends thereof. Two rods 92 and 93 pass through the sleeves 94 and 95 and also through the plates 88 and 89. These rods are threaded at the centers thereof, as designated at 96, to receive nuts 97 by means of which the two plates 25 88 and 89 may be clamped together and against the two spacer sleeves 94 and 95 to hold the parts of the yoke rigidly attached to one another in proper spaced relation.

The block 91 consists of two halves 98 and 99 30 which are bolted together through bolts 100. By means of this construction the block 91 may be readily assembled upon the crank pin 44. This block is so constructed as to be slidably received within the slot 90. For the purpose of taking up 35 wear in the cross head 87, shims 101 are employed between the halves 98 and 99 of block 91 and other shims 102 between the sleeves 95 and the respective plates 88 and 89 of the yoke proper.

The yoke 87 is guided for reciprocating movement in the direction of movement of the various pistons 81, 82, 83, 84, 85 and 86 as follows: In the bottom 15 and in closure 32 are formed openings 103 and 104 which extend throughout a portion of the width of the crank case. These 40 openings are centrally disposed with respect to the crank pin 44. Attached to the bottom 15 and to top 32 through bolts 105 are two cover plates 106 and 107. These cover plates have ways 108 formed in the same in which suitable guides 50 117 secured to the yoke 87 may slide. These guides are attached to the ends of the plates 88 and 89 through bolts 118 which are screwed in the same. By means of these guides and ways 55 the yoke 87 is mounted for translatory reciprocating movement in a direction parallel with the direction of reciprocation of the various pistons of the engine.

The two rods 92 and 93 used for connecting the plates 88 and 89 of the yoke 87 together are also 60 employed as connecting rods for connecting certain of the pistons of the engine together. The rod 92 is so disposed that the axis thereof lies in alignment with the axis of the two pistons 81 and 84. This rod is also threaded at its ends as indicated at 109 to screw into bosses 110 formed in each of the pistons 81 and 82. Lock nuts 111 also threaded upon the threaded portions 109 of said rod holds the respective pistons in rigid position upon the end of this connecting rod. The rod 93 is similarly utilized to connect the two pistons 83 and 86 together. Pistons 82 and 85 are also rigidly connected to the cross head 87. For this purpose two piston rods 112 and 113 are employed which are attached to said pis- 70 75

tons in identically the same manner as the two rods 92 and 93. These rods are provided at their inner ends with threads 114 which are screwed into suitable bosses 115 formed at the centers of the two plates 88 and 89. Lock nuts 116 screwed upon the ends of these rods and abutting against the bosses 115 hold the rods 112 and 113 rigidly attached to the cross head 87. By means of this construction all of the pistons 81 and 88 travel in unison and move the cross head in a manner to cause the block 91 to reciprocate along the slot 80 and procure rotational movement of the crank shaft 25.

For procuring operation of the various valves 74 and 75 of the cylinders of the unit the following construction is employed: In the crank case 10 are journaled six cam shafts 119, 120, 121, 122, 123 and 124, two of which are utilized for each of the respective cylinder units 51, 52 and 53. The two cam shafts 119 and 120 operate the valves for unit 53. These shafts are journaled in bearings 125 which are attached to the bottom 15 and cover plate 32 of the crank case 10 and are provided with spiral gears 126 and 127 which mesh with a spiral gear 228 formed on the shaft 48 of crank shaft 25. On the shaft 119 are six cams 128, 129, 130, 131, 132 and 133. These cams operate valve lifters 134 which are slidably mounted in guides 135 formed on the end wall 11 of the crank case proper. The various valve lifters have threaded into the free ends thereof push rods 136 which are connected at their upper ends to rocker arms 137 best shown in Fig. 1. The rocker arms are mounted upon a shaft 138 which is rigidly secured in bearings 139 mounted on the cylinder head 69. The rocker arms 137 engage the valve stems 71 of the various valves and press the valves inwardly in opposition to the springs 88, opening the valves and admitting gases to and from the cylinders proper. All of the cylinders have similar valves and operating mechanism therefor which are operated by the various cam shafts associated therewith through cams, valve lifters, push rods and rocker arms the same as the valves of cylinder unit 54.

For the purpose of igniting the fuel mixture introduced into the various cylinders, spark plugs 140 are employed which are screwed into the cylinder heads 69. These spark plugs are fired in the usual manner through two ignition and timing mechanisms of ordinary construction which have been designated by the reference numerals 200 and 201 in the drawings. These devices are operated from the two cam shafts 119 and 120. It can readily be comprehended that any suitable mechanism of the type now in common use may be employed for this purpose. Where the dual cylinders are separately fired the spark plugs therefor are connected to both of the timing devices 200 and 201 which of course have separate spark coils or a single spark coil with separate windings. If desired however, the two explosion chambers of the dual cylinders may be connected together and fired by a single spark plug.

The firing order of the various cylinders of the invention and the cycle of operation of the same is shown in Fig. 5. In this view the cylinders have been arranged in groups to correspond to the units 51, 52 and 53 which are represented by similar reference characters. In Fig. 5 the upper cylinders are those situated to the left of the crank shaft and the lower cylinders are those at the right of the crank shaft and in the various views the cylinders have been designated by the

same reference characters. The diagrammatic views shown represent the travel of the cams on the two cam shafts of the unit. Considering cylinder 57 as firing at position 141 the period of explosion would be represented by the solid portion of the diagram designated by reference character 142. The exhaust valve would open shortly before lower dead center which would be at position 143 and the cylinder would continue to exhaust throughout the period designated by reference character 144. At position 145 the exhaust valve would close and the intake valve would open, this position being at opposite dead center. Intake would then occur for the down stroke and during the period 146, the intake valve closing at position 147, which is somewhat past lower dead center 148. Compression would then occur during period 149 until the pistons reach upper dead center, which position is indicated at 141 after which the cycle of operation would be repeated. It will be noted that the action in cylinder 60 is identically the same as that in cylinder 57 excepting that the cycle of operation is 90 degrees advanced from the cycle of operation of cylinder 51, which would be equivalent to 180 degrees or half a revolution of the crank shaft. It will be further noted that both cylinders 56 and 58 operate in unison and likewise cylinders 59 and 61 operate in unison. The cycle of operation of cylinder 57 is exactly 180 degrees in advance of the cylinder 60 or one complete revolution in advance when compared to the crank shaft. Likewise cylinders 59 and 61 are 180 degrees in advance of cylinder 60 or one complete revolution in advance thereof as compared to the crank shaft. Again cylinders 59 and 61 are 90 degrees in advance of cylinders 56 and 58 the same as cylinder 60 is 90 degrees in advance of cylinder 57.

On account of the particular arrangement of cylinders and the firing order thereof, it will be found that the cylinder 57 is exploding while the cylinder 60 is under compression. Likewise cylinders 56 and 58 are exploding while cylinders 59 and 61 are under compression. By means of this construction the compression of one cylinder acts as a cushion for another cylinder whose pistons are directly connected, whereby the momentum and impulses from the power cylinder are partially absorbed through compression in the opposite cylinder. The area of the two outer cylinders is made equal to the inner cylinder so that the impulse is the same whether the center or the outer cylinders are being fired and likewise whether the cylinders on one side of the crank shaft or the other are being fired. By means of this construction, two equal and uniformly spaced impulses are had per revolution on each crank pin. The units 52 and 53 are arranged in identically the same manner as the unit 51 with the various cylinders thereof being fired in the same relative order as the cylinders of unit 51. However, the cylinders of this unit are fired 120 degrees later than the cylinders of unit 51 and the cylinders of unit 53 are fired 240 degrees later than unit 51. With this arrangement of parts the equivalent of a twelve cylinder engine is procured through the use of but three crank pins.

In the operation of our invention the power is uniform applied through equal impulses to the crank shaft, uniformly distributed throughout the rotation of the same. Due to the fact that the outer cylinders are fired simultaneously, the resultant of the pressures applied to these two cylinders is directed along a line which coincides

with the resultant of the pressures applied to the central cylinder so that the firing of either the outer or the inner cylinders acts in exactly the same manner upon the crank pin. By the use 5 of the yoke and through the pistons directly connected to the same through fixed connecting rods, no lateral forces are applied to the pistons. The cushioning of the one cylinder through the other is procured through rigid means directly connecting the pistons of the relative cylinders. This eliminates the necessity of transmitting such cushioning through the bearings of the crank shaft and consequently reduces wear on the crank shaft and its bearings. By means of our 10 improved construction, wrist pins and pivoted connecting rods are eliminated, thereby greatly reducing friction and increasing the economical performance of the engine. With our invention the piston units are symmetrical and completely 15 balanced. Due to the use of a yoke instead of a swinging connecting rod in transmitting the translatory movement of the pistons to the crank shaft, the power is transmitted through a greater angle of rotation than would be the case where 20 a swinging connecting rod were employed. By means of the guides on the top and bottom of the yoke the alignment of the pistons and yoke is permanently maintained and the moving parts caused to move in a direct rectilinear path. 25 Through suction and firing on one side of the crank shaft simultaneously with compression and exhaust on the other side, the motor is more nearly balanced and the positive forces caused to directly neutralize the negative forces tending 30 to produce rotation of the crank shaft. With our invention the cylinders and pistons will not wear out of round. Considerably more power may be procured from a unit of given overall dimensions constructed in accordance with our 35 invention and at the same time considerably less weight is required. With our invention a much shorter crank shaft can be employed and consequently more rigid construction results in which vibration is greatly lessened. The transmission 40 of power to the crank shaft is always in the same direction throughout the entire movement of the pistons so that more uniform torque is 45 procured on the crank shaft. By the use of the yoke instead of a swinging connecting rod lateral movement of the connecting rods is eliminated. With our invention each yoke takes 50 the place of four connecting rods and the number of bearings in the engine can be correspondingly reduced including both main bearings, crank 55 pin bearings and wrist pin bearings, the latter being entirely eliminated. Due to the particular method of application of the power to the crank shaft by use of the yoke, power is transmitted to the same throughout a greater angle of 60 rotation of the crank shaft and the exhaust valves may hence be kept closed for a greater angular distance during the impulse stroke than would otherwise be possible. With our invention piston 65 slap and cocking or binding of the pistons is entirely prevented. The energy lost in the swinging connecting rods is also eliminated with our invention. Due to the fact that the outer pistons are of a combined total area equal to the area of the center piston constant balance is 70 maintained throughout the operation of the engine. The pistons may be removed from the rods without taking down the motor but merely removing the cylinder blocks in which they operate. Thereafter the ratio of compression may

be changed by merely changing the position of the pistons upon the connecting rods.

Changes in the specific form of our invention, as herein disclosed, may be made within the scope of what is claimed without departing from 5 the spirit of our invention.

Having described our invention, what we claim as new and desire to protect by Letters Patent:

1. An engine comprising a crank shaft, a yoke 10 connected to said crank shaft, and movable in a direction at right angles to the axis of the crank shaft, a cylinder disposed on one side of said crank shaft with its axis extending in the same direction as the direction of movement of said 15 yoke and lying in a plane containing the axis of said crank shaft, a pair of cylinders disposed one on each side of said aforementioned plane, the axes of said cylinders being equally spaced from said plane and parallel therewith and lying in a 20 plane at right angles to said first plane and containing the axis of said first named cylinder, said last named cylinders being connected together, pistons in said cylinders and means for rigidly connecting said pistons to said yoke. 25

2. An engine comprising a crank shaft, a yoke connected to said crank shaft, and movable in a direction at right angles to the axis of the crank shaft, a cylinder disposed on one side of said crank shaft with its axis extending in the same 30 direction as the direction of movement of said yoke and lying in a plane containing the axis of said crank shaft, a pair of cylinders disposed one on each side of said aforementioned plane, the axes of said cylinders being equally spaced from 35 said plane and parallel therewith and lying in a plane at right angles to said first plane and containing the axis of said first named cylinder, said last named cylinders being connected together, pistons in said cylinders and means for rigidly 40 connecting said pistons to said yoke, said second named cylinders having a combined displacement substantially equal to that of said first named cylinder.

3. In an engine, a crank shaft, a piston structure disposed on one side thereof, a second piston structure disposed on the same side thereof, the arrangement of said piston structures being such that the position of the resultant of the pressure acting on the one piston structure is substantially 50 the same as the position of the resultant of the pressure acting upon the other piston structure, a third piston structure disposed on the side of said crank shaft opposite said first piston structure, a fourth piston structure disposed on the 55 same side of said crank shaft as said third piston structure, the arrangement of said third and fourth piston structures being such that the position of the resultant of pressure acting on the third piston structure is substantially the same 60 as the position of the resultant of the pressure acting upon the fourth piston structure, and substantially the same as the positions of the resultants of the first and second piston structures, means for rigidly connecting all of said piston structures together and for imparting rotational movement to said crank shaft. 65

4. In an engine, a crank shaft, a cylinder disposed on one side of said crank shaft with its axis at right angles to the axis of said crank shaft 70 and constituting a cylinder unit, a group of cylinders, symmetrically grouped about said first cylinder and having their axes parallel with the axis of said first cylinder, the cylinders of said group being all interconnected and constituting 75

- a second cylinder unit, a cylinder on the opposite side of said crank shaft in axial alignment with said first named cylinder and constituting still another cylinder unit, a group of cylinders symmetrically grouped about said last named cylinder, said last named group of cylinders having their axes parallel to the axis of said last named cylinder and constituting a fourth cylinder unit, pistons in said cylinders, means for rigidly connecting all of said pistons together and for imparting rotational movement to said crank shaft.
5. In an engine, a crank shaft, a cylinder disposed on one side of said crank shaft with its axis at right angles to the axis of said crank shaft and constituting a cylinder unit, a group of cylinders, symmetrically grouped about said first cylinder and having their axes parallel with the axis of said first cylinder, the cylinders of said group being all interconnected and constituting 10 a second cylinder unit, a cylinder on the opposite side of said crank shaft in axial alignment with said first named cylinder and constituting a third cylinder unit, a group of cylinders symmetrically grouped about the cylinder of said third cylinder unit and disposed on the same side of the crank shaft as the cylinder of said third cylinder unit, said last named group of cylinders being connected together and having their axes parallel 15 to the axis of the cylinder of said third cylinder unit, means for charging all of said cylinders with a fuel mixture, means for alternately firing the cylinder units on each side of the crank shaft and for alternately firing cylinder units on opposite 20 sides of the crank shaft, the firing of one cylinder unit occurring during compression of the fuel mixture in a unit on the other side of the crank shaft, pistons in said cylinders and means for imparting rotational movement from said pistons 25 to said crank shaft.
20. In an engine, a crank shaft, a cylinder disposed on one side of said crank shaft with its axis at right angles to the axis of said crank shaft and constituting a cylinder unit, two cylinders symmetrically grouped about said first cylinder and having their axes disposed in the plane containing the axis of the first cylinder and at right angles to the axis of the crank shaft, the two 25 cylinders being interconnected and constituting a second cylinder unit, a cylinder on the opposite side of said crank shaft and in axial alignment with said first named cylinder and constituting a third cylinder unit, two cylinders symmetrically grouped about the cylinder of said third cylinder unit and disposed on the same side of the crank shaft as the cylinder of said third cylinder unit, said last named cylinders being connected together and disposed with their axes in said aforementioned plane, pistons in all of said cylinders, and means for rigidly connecting all of said pistons 30 to said crank shaft.
